UNITED STATES PATENT OFFICE.

HENRY G. THOMPSON, OF NEW YORK, N. Y.

IMPROVEMENT IN MACHINERY FOR SIZING THE BACKS OF CARPETS.

Specification forming part of Letters Patent No. 36,738, dated October 21, 1862.

To all whom it may concern:

Be it known that I, HENRY G. THOMPSON, of the city, county, and State of New York, have invented a new and useful Machine for Sizing the Backs of Brussels and Velvet and other like Carpets; and I do hereby declare that the following is a full, clear, and exact description thereof, reference being had to the accompanying drawings, making part of this specification, in which—

Figure 1 is a plan of the machine without the carpet in it, the better to exhibit the arrangement of the parts. Fig. 2 is an elevation of the right-hand side of the machine; Fig. 3, an elevation of the left-hand side, and Fig. 4, a longitudinal vertical section with the carpet in position.

The same letters indicate like parts in all the figures.

The object of my said invention is to size the backs of that class of carpets which are woven on a plain back with a pile on the upper surface, and in which the pile is formed over wires or equivalent means in the act of weaving—such as Brussels and velvet carpets. In the manufacture of such fabrics it has been the practice to size the back, for the purpose of contracting the fabric by the action of the moisture of the sizing matter on the threads of the web, to render the pile on the face of the fabric more compact, and to give more stiffness to the whole fabric when the sizing dries. The sizing has heretofore been applied with a hand-brush and dried in the atmosphere or by heated air; but this mode of procedure is very laborious, the sizing matter fails to enter to a sufficient extent into the web of the fabric, and in drying does not leave the fabric sufficiently smooth. By my said invention I overcome all these difficulties.

In the accompanying drawings, *a* represents a suitable frame, and *b* a smooth free roller under which the carpet *c* to be sized passes, and *d* another roller over which the carpet passes. The periphery of this roller is armed with fine teeth or points to hold onto the under surface or back of the carpet as it passes over it, the shaft of the said roller being provided at each end with a friction-pulley, *d*¹ *d*², and friction-brake to make sufficient friction to hold back the carpet when pulled through by machinery at the other end, that it may be under tension during the operations of sizing

and drying. The friction of the brakes can be regulated at pleasure by screws or other well-known equivalent means to regulate the tension. From the last-described roller the carpet passes under an inverted table, *e*, which is supported at the four corners by rods *f* *f*, on which it can slide for adjustment by nuts, above and below it, and tapped onto the vertical rods *f* *f* *f* *f*. The face of the pile of the carpet passes in contact with the under face of the said table, and thence passes over supporting-rollers *g* *g*, to and over a hollow drying and smoothing cylinder, *h*, to the mechanism by which it is drawn along through the machine by a regular motion. This drawing mechanism consists of a roller, *i*, armed on its periphery with pins to take into the web, and it receives motion from the main driving-shaft *j* by a belt, *k*, and train of cog-wheels and pinions *k* *l* *m* *n*, and this roller in turn communicates motion to two other rollers, *o* *p*, by a train of cog-wheels, *q* *r* *s*. The carpet from the drying and smoothing cylinder passes around the roller *i* on the inside, under it, thence over and under the roller *o*, and over the roller *p*, by which it is dropped onto the floor or a suitable platform for the purpose.

As the carpet is drawn with a regular motion by this mechanism, and the roller *d* at the other end, over which it passes, is controlled by an adjustable friction-brake, any degree of tension can be given to it in its passage through the machine.

Below the inverted table *e* there is a rotating brush, *t*, formed of rows of stiff bristles projecting from the surface of a cylinder, and so placed relatively to the under surface of the table *e* that while the pile or face of the carpet passes in contact with and is kept smooth and even by the under surface of the table, the brush acts with considerable force against the under face or back for the purpose of applying the sizing-matter to such surface and forcing it into the meshes of the web. The brush is rotated in the direction of the arrow (see Fig. 2) by a belt, *u*, from a pulley, *v*, on the driving-shaft, to a pulley, *w*, on the shaft of the brush.

The liquid sizing-matter, prepared in the usual manner for sizing fabrics, is contained in a vat, *x*, from which it is taken by a roller, *y*, the lower part of which runs in the sizing, and from the periphery of this roller it is

taken up by the periphery of another roller, z , and presented to the rows of bristles of the rotating brush, by which it is taken and applied, as described.

Motion is communicated to the rollers y and z from a pulley, a' , (see Fig. 3,) on the shaft of the brush by belts and pulleys $b' c' d' e' f'$ and train of cog-wheels $g' h' i' i''$.

If desired, the position of the roller y relatively to the roller z may be made adjustable by any of the well-known modes, for the purpose of varying the supply of sizing-matter to the brush.

Between the rotating brush and the drying-cylinder h there is a series of longitudinal steam-pipes, j' , connected at their ends with two cross-pipes, k' and l' . The pipe k' is to be connected by a branch pipe, m' , with any suitable steam-generator, and the other, l' , provided with a discharge-pipe, n' , to carry off the steam and water of condensation.

The pipes are to be heated by the circulation of steam through them, and the heat radiated from them, and the current of heated air induced by the rotating fan t' on the vertical shaft u' will partially dry the sizing-matter applied to the under face of the web, so that it shall not adhere and accumulate on the surface of the cylinder to which it next passes, and whose office it is to finally dry the sizing and keep the under surface of the carpet smooth and even during such final drying.

The hollow cylinder h is heated by steam, the journals $o' o'$ being hollow and adapted in any of the well-known modes to turn on pipes $p' p'$, one of them connected with a steam-generator to supply the steam, and the other for the discharge of the steam. The periphery of this hollow cylinder should rotate in a direction the reverse of the motion of the carpet, and such required motion is imparted to the cylinder by the cog-wheel n on the shaft of the roller i , and a train of wheels, $q' r' s'$.

After the carpet has been thus treated it will be found that the pile is more compact and smooth, and that the carpet will lie bet-

ter on a floor than when sized by hand as heretofore practiced.

It will be obvious that the series of pipes and the drying-cylinder may be heated by the circulation of heated atmospheric air instead of steam, although I prefer the use of steam; and it will also be obvious that the sizing applied to the carpet may be partially dried as it passes to the drying-cylinder by a blast of heated air instead of heated pipes; and it will also be obvious that other and equivalent means may be substituted for the mechanism herein described for drawing the carpet regularly through the machine and keeping it distended while the sizing is applied and dried; and that instead of making the table adjustable relatively to the brush, the table may be permanent and the brush made adjustable.

What I claim as my invention, and desire to secure by Letters Patent in machinery for sizing carpets, is—

1. The combination of the rotating brush and the adjustable table, for the purpose described, the distance between the two being adjustable, substantially as and for the purpose described.

2. The combination of the rotating brush and table, with the mechanism for moving and keeping the carpet distended, substantially as and for the purpose set forth.

3. The combination of the rotating brush, the table, the mechanism for moving the carpet and keeping it distended, and the drying and smoothing cylinder, substantially as and for the purpose described.

4. The combination of the rotating brush, the table, the mechanism for moving and keeping the carpet distended, the drying and smoothing cylinder, and the interposed drying apparatus, or the equivalent thereof, for partially drying the sizing before it reaches the surface of the drying-cylinder, substantially as described.

HENRY G. THOMPSON.
